(57) **CLAIM**

The ornamental design of the cutting board with sharpener, as shown.

DESCRIPTION

FIG. 1 is a perspective view of a cutting board with sharpener showing my new design.

FIG. 2 is a top view thereof.

FIG. 3 is a front view thereof.

FIG. 4 is a bottom view thereof.

FIG. 5 is a back view thereof.

FIG. 6 is a right side view thereof; and,

FIG. 7 is a left side view thereof.

The invention pertains to an ornamental design for an article of manufacture, which can be scaled to different sizes.
